No. 727,979.

Patented May 12, 1903.

UNITED STATES PATENT OFFICE.

JOHN BRACHE LE MAITRE, OF NEAR BIRMINGHAM, ENGLAND.

DOOR AND WINDOW FOR CARRIAGES.

SPECIFICATION forming part of Letters Patent No. 727,979, dated May 12, 1903.

Application filed December 5, 1902. Serial No. 134,015. (No model.)

To all whom it may concern:

Be it known that I, JOHN BRACHE LE MAITRE, a subject of the King of Great Britain, residing at 45 Grantham road, Sparkbrook, 5 near Birmingham, in the county of Warwick, England, have invented certain new and useful Improvements in and Relating to Doors and Windows for Carriages and to the Mode and Means for Operating the Same, of which

10 the following is a specification.

My invention has for its object improvements in and relating to railway-carriage and other windows and to the mode and means for operating the same by which such windows and sashes can be raised and lowered or fixed in any intermediate position with greater facility.

15 The accompanying drawing is a front elevation of the inside of a railway-carriage door 20 with my invention applied thereto.

Suitably mounted on the front of the door on the inside of the compartment in any desired or suitable position is the disk wheel *a*, having the handle *b*, and also mounted on 25 the disk-wheel spindle is the sprocket-wheel *c*. Mounted on the sprocket-wheel *c* is the endless chain *g*, which also passes around

the pulley *j*, hung on the inside of the door. A second chain is secured at one end to the chain *g* at *q*, the other end of this chain passing down and around the pulley *k*, hung to the bottom of the window *i*, the end of the chain being attached to the hook *l*, which is secured to the door-frame. By turning the disk wheel *a* by the handle *b* the window *i* is 35 raised and lowered with great ease.

My improved means for raising and lowering windows is also specially suitable for road-carriages, cabs, and the like.

What I claim, then, is—

30 The combination with a window and its frame, of pulleys mounted on said frame, an endless chain carried by said pulleys, a pulley attached to the window, and a chain having one end fixed to the frame and the other 35 end passed around said pulley on the window and attached to the endless chain.

40 In witness whereof I have hereunto set my hand in presence of two witnesses.

JOHN BRACHE LE MAITRE.
